UNITED STATES PATENT OFFICE.

CLAUDE E. WING, OF COLLEGE POINT, AND HERMAN SCHELHAMMER, OF WHITE STONE LANDING, NEW YORK, ASSIGNEES TO AMERICAN HARD RUBBER CO., OF NEW YORK, N. Y., A CORPORATION OF NEW YORK.

MACHINE FOR MAKING COMBS.

1,423,981.

Specification of Letters Patent. Patented July 25, 1922.

Application filed April 22, 1921. Serial No. 463,708.

To all whom it may concern:

Be it known that we, CLAUDE E. WING, residing at College Point, in the county of Queens and State of New York, and HERMAN SCHELHAMMER, residing at Whitestone Landing, in the county of Queens and State of New York, both citizens of the United States, have jointly invented new and useful Machines for Making Combs, of which the following is a description, such as will enable others skilled in the art to which it appertains to make and use the same.

This invention relates to machines for making combs, and the objects of the invention are to provide a machine for cutting or sawing the molded teeth of a comb in an economical manner that is automatic in operation.

To the accomplishment of the above objects and to such others as may hereinafter appear, the invention comprises means whereby a comb blank in which is molded both coarse and fine teeth may be cut simultaneously, or a comb blank in which is molded all coarse teeth or all fine teeth may also be cut simultaneously by a pair of cutters automatically controlled by suitable mechanism.

Further objects of the invention are to provide means whereby the cutters are given automatic forward and backward oscillatory cutting movement in a plane at right angles to the comb blank, and progressive step feed movements longitudinally of, or parallel with, the comb blank. Further objects of the invention are to provide means for bracing the comparatively thin fine tooth cutter against lateral bending at the beginning of the cutting operation to produce a uniform straight initial cut.

The invention is now to be described with reference to the accompanying drawings which form part of this specification and in which similar reference characters are employed to indicate like parts throughout the several views, in which—

Figure 1 is a front elevation of the improved comb cutting machine with parts omitted for clearness of illustration.

Figure 2 is a vertical cross section taken on the line of 2—2 of Figure 1.

Figure 3 is a horizontal section taken on the line 3—3 of Figure 1.

Figure 4 is a detail of the comb clamp in its support.

Figure 5 is a fragmentary face view of the comb clamp looking in the direction of the arrow 5 of Figure 4.

Figure 6 is a detail elevation of a feed cam and associated parts.

Figure 7 is a side elevation of the fine tooth cutter and its associated parts showing the position assumed at the beginning of the cut.

Figure 8 is a view similar to Figure 7 with the parts in the position assumed at the end of the cut.

Figure 9 is a detail of a portion of Figure 8 on an enlarged scale.

Figure 10 is a sectional detail on the line 10—10 of Figure 5.

In the drawings, 1 designates a bed plate to which is bolted a frame 2 formed with bearings 3 for a drive shaft 4 on which is carried a pair of pinions 5 meshing with large gears 6 on stud pins 7. Other but smaller gears 8 are fast to and rotatable with the gears 6 and are in mesh with large gears 9 carried on cam shafts 10 journaled at one end in the frame 2 and at the other end in a standard bearing 11.

Loosely suspended on the shaft 4 are cutter frames 12 and 13 which carry respectively a fine tooth cutter 14 and a coarse tooth cutter 15 fixed to rotatable shafts 16 and 17, driven respectively by means of sprockets 18 and 19, through the medium of chains 20 and 21 connected to drive sprockets 22 and 23 splined to the shaft 4 and confined in forks 24 of the cutter frames 12 and 13.

The cutter frames 12 and 13 are provided with rearwardly directed arms 25 having midway of their length fixed nuts 26 provided with parallel threads which mesh with threaded cams 27 the same being held in engagement by weights (not shown) suspended on links 28 carried on the rear ends of the arms 25.

As the cams 27 act to oscillate the cutters 14 and 15 to cut the comb teeth, means are provided for automatically stopping the oscillatory movement of the cutters after the last tooth has been cut in the comb blank, the same comprising hooks 29 on the arms 25 which when the cutters are oscillated rear-

wardly after the last tooth has been cut by the action of the cams 27, which also act to move the cutters laterally, to thereby engage adjustable trip fingers 30 which act to automatically stop the oscillatory movements of the cutters, as shown in Figure 2 of the drawings.

To accurately regulate the forward, oscillatory limit of the cutters to thereby predetermine the length of the teeth of the comb blank there is provided on the cutter frames 12 and 13 adjustable pins 31, which at the extreme inner limit of the cut, contact with stop plates 32 bolted to the top of the frame 2.

In order to oscillate the cutters 14 and 15, the cams 27 are made ellipsoidal, the threads thereon being parallel with the sides except at the high point 33 where they incline to one side the width of one thread, so that, in the present instance, at each revolution of the cams 27, the cutter frames are moved along the shaft 4, one step, and owing to their peripheral contour oscillate the cutter frames 12 and 13, as before described, positively in one direction and permit of their oscillation in the reverse direction by the weights hereinbefore referred to.

It is of course to be understood that the lateral feeding movement of the cutter frames may be made greater or less by providing cams 27 and nuts 26 having different thread inclinations depending upon the comb blank teeth to be cut.

It will also be understood that one of the nuts 26 and the corresponding cam 27 may be provided with left hand threads and the other with right hand threads for feeding the frames 12 and 13 in opposite directions.

Mounted at the front of the base 1 is a clamp frame 34 comprising a clamp base 35, end standards 36, having bearings at the top for trunnions 37, of a comb clamp 38 holding, in the present instance, a pair of comb blanks 39. As the comb clamp forms no part of the present invention it will not be further described. The clamp frame 34 may be adjusted with respect to the cutters by a screw 40 swiveled in a cross bar 41 and threaded through a lug 42 on the clamp base 35.

In the molding of comb blanks more stock is left in the web portions between the coarse teeth than between the web portions of the fine teeth, and as it is necessary to cut a few fine teeth in order to provide clearance for the coarse tooth cutter before it can be positioned, it is desirable to brace the fine tooth cutter when the initial fine tooth cut is made as there is a tendency for the fine tooth cutter to bend and follow the line of least resistance or away from the coarse tooth end of the blank. In order to obviate this difficulty there is provided a yoke 43, pinned to a bar or shank 44, slidably carried in bearings 45

on the arms 12 and threaded at 46 to receive a nut 47 provided with an arm 48. The yoke 43 has a pair of lugs 49 which bear against the sides of the cutter 14 and before the initial fine tooth cut is made the arm 48 with its nut 47 is swung down from the position shown in Figure 7 to the position shown in Figure 8 where it is held against the tension of a spring 50 by a catch 51, held in elevated position by a spring 52. The catch 53 is pivotally mounted to the lower end of the cutter frame 12 and is provided with a tail piece 53 arranged to strike a stop 54, to trip the catch 51, to thereby release the arm 48 as the cutter frame 12 swings back out of the comb blank after the initial fine tooth cut has been made. When the nut 47 is turned by moving the arm 48 into engagement with the catch 51, the threaded bar 44 and with it the yoke 43, is moved slightly to the right as seen in Figure 1 which acts to bend the cutter 14 slightly to the right and in this position the cutter 14 enters the comb blank for the initial fine tooth cut. The slight bend of the cutter compensates for the greater resistance of the comb stock adjacent the coarse teeth resulting in a straight initial fine tooth cut; after which, as above described, the arm 48 is released by the catch 51, and the yoke 43 is returned to normal position by the spring 50, the nut 47 acting to draw the yoke 43 to the left, permitting the cutter 14 to spring back to normal straight position.

When, as in the present instance, two comb blanks 39 are inserted in the clamp 38 it is essential to have them in perfect registration or alignment, so that the teeth of the two comb blanks are directly opposite. In order to accomplish the alignment of the teeth, a gauge pin 56 is provided, slidably mounted in a bracket 57, on an arm 58 carried on one of the standards 36, the gauge pin 56 being arranged to enter the groove between the first and second teeth of each comb before being clamped in position, as shown in Figures 5 and 10. After the clamp 38 has been tightened the gauge pin 56 is removed and the clamp 38 returned to normal operative position, as shown in Figure 2.

The cutters are guided as they cut the webs between the teeth of the comb blanks by means of a guide pin 59, adjustably carried in a holder 60, pivoted at 61 to an adjustable bracket arm 62, carried on a guide frame 63 loosely mounted on a bolt 64 secured to the cutter frame. The guide frame 63 has a shoulder 65 and a lug 66 threaded to receive a stop screw 67 locked in adjusted position by a nut 68. A spring 69 fastened to the lug 66 and to the cutter frame, acts to hold the screw 67 against a stop 70, carried on an extension 71 of the cutter frame.

Another spring connected at one end to an arm 72, formed on the guide pin holder 60, and at the other end to a fixed lug 73, on the bracket arm 62, acts to hold an adjustable threaded pin 74 against a stop 75.

The above construction provides yielding supports for the guide pins 59 so that they can adjust themselves to varying depths of grooves between the comb blank teeth, and 10 also permits the guide pins 59 to ride up over the teeth and down into the adjacent grooves as the cutters are moved along the face of the comb by the action of the cams 27. The noses of the guide pins 59 follow 15 up the bottom of the groove next adjacent the one being cut and effectively hold the cutters and the cutter frames against vibration or side play.

The cutter frames 12 and 13 are provided 20 with suitable handles 76 by means of which the cutter frames and associated parts can be moved along the shaft 4 in either direction.

In the operation of the machine the cutter 25 frames 12 and 13 are moved to the ends of the machine on the shaft 4 and the comb blanks placed in the clamp which is then turned up into the position shown in Fig. 4, the pin 56 being inserted between the comb 30 blanks to properly align them, after which a suitable clamp screw 77 is operated to lock the clamp. The pin 56 is then raised from between the comb blanks and the clamp is turned down to operative normal position, as 35 shown in Figure 2. The cutter frame 12 carrying the fine tooth cutter is then brought over from the left of the machine to a point where the guide pin 59 enters the second fine tooth groove from the centre of the comb 40 blank. The machine is then started, and after about five teeth have been cut, the machine is preferably stopped and the cutter frame 13, carrying the coarse tooth cutter is brought over from the right to a point where 45 the guide pin 59 will enter the second coarse tooth groove from the centre of the comb blank, and the machine is again started, after which the operations are automatic.

While the invention has been described 50 with reference to cutting on the same comb blank both fine and coarse teeth, the machine is equally applicable to being used to cut comb blanks having either all fine teeth or all coarse teeth.

55 While the invention has been described with particular reference to the details of construction the same is not to be considered as limited thereto, as many changes can be made and still fall within the scope of the invention set forth in the following claims.

60 What we claim is:—

1. A comb cutting machine comprising in combination a plurality of revoluble cutters, means for oscillating said cutters, and means 65 for feeding said cutters simultaneously in

opposite directions longitudinally of said machine.

2. A comb cutting machine comprising in combination a plurality of cutters, a comb clamp for holding a comb blank, means for oscillating said cutters toward and away from said comb blank, means for feeding said cutters simultaneously in opposite directions across the face of said comb blank, and means for stopping the operation of said 75 cutters when the comb is complete.

3. A comb cutting machine comprising in combination a rotary cutter, a comb clamp for holding a comb blank, means for oscillating said cutter toward and away from 80 said comb blank, means for feeding said cutter across the face of said comb blank, and means for bending the cutter to compensate for side thrust on the initial cut.

4. A comb cutting machine comprising in 85 combination a fine cutter and a coarse cutter, a comb clamp for holding a comb blank having fine and coarse teeth, means for oscillating said cutters toward and away from said comb blank, means for feeding said cutters 90 across the face of said comb blank, and means for bending the fine cutter to compensate for side thrust on the initial cut.

5. A comb cutting machine comprising in combination a rotary cutter, a comb clamp 95 for holding two comb blanks, means for pivotally supporting said comb clamp, a gauge pin to register said comb blanks one with the other, and means for supporting said gauge pin above said comb clamp.

6. A comb cutting machine comprising in combination a comb clamp for holding a comb blank, a cutter frame, a cutter rotatably mounted on said cutter frame, means for oscillating said cutter frame and with it said 105 cutter toward and away from said comb blank, and a yoke engaging the side of the cutter, and means for causing the yoke to bend the cutter to compensate for side thrust during the initial cut.

7. A comb cutting machine comprising in combination a comb clamp for holding a comb blank, a cutter frame, a cutter rotatably mounted on said cutter frame, means for oscillating said cutter frame and with it said 115 cutter toward and away from said comb blank, a yoke engaging the side of the cutter, means for causing the yoke to bend the cutter to compensate for side thrust during the initial cut, and means for releasing the yoke 120 after the initial cut has been made.

8. A comb cutting machine comprising in combination a comb clamp for holding a comb blank, a plurality of cutter frames, cutters rotatably mounted on said cutter frames, 125 means for oscillating said cutter frames and said cutters toward and away from said comb blank, means for giving said cutters progressive step movements across the face of the comb blank, and adjustable means on 130

said cutter frames to regulate the limit of cutting movement of said cutters.

9. A comb cutting machine comprising in combination a comb clamp for holding a comb blank, a plurality of cutter frames, cutters rotatably mounted on said cutter frames, means for oscillating said cutter frames and said cutters toward and away from said comb blank, means for giving said cutters progressive step movements across the face of the comb blank, a yoke engaging the sides of one cutter, and means for causing the yoke to bend the cutter to compensate for side thrust during the initial cut.
10. 10. A comb cutting machine comprising in combination a comb clamp for holding a comb blank, a plurality of cutter frames, cutters rotatably mounted on said cutter frames, means for oscillating said cutter frames and said cutters toward and away from said comb blank, means for giving said cutters progressive step movements across the face of the comb blank, a yoke engaging the sides of one cutter, means for causing the yoke to bend the cutter to compensate for side thrust during the initial cut, and means for releasing the yoke after the initial cut has been made.
11. In a comb cutting machine, the combination of a rotary cutter, means for oscillating said cutter and for feeding said cutter longitudinally of said machine, and adjust-

able means for limiting the inward oscillatory movement of said cutters.

12. A comb cutting machine comprising a swingable comb clamp for holding a pair of comb blanks, means for aligning said blanks comprising an adjustable pin adapted to enter one of the grooves in said blank when said clamp and said blanks are brought into aligning position, and means for simultaneously cutting teeth in said blanks, after alignment.

13. In a comb cutting machine for cutting teeth in comb blanks having molded grooves therein, revoluble cutters for sawing said teeth, and means for guiding said cutters comprising an adjustable finger adapted to engage that groove of said blank adjacent the tooth to be cut, a spring for urging said finger toward the bottom of the groove to be cut, a stop pin for limiting the downward movement of said finger, and a yieldable support for said finger for allowing said finger to ride over the ridge of one groove to the next succeeding groove.

In testimony whereof we have signed this specification in the presence of two subscribing witnesses.

CLAUDE E. WING.
HERMAN SCHELHAMMER.
